Design No. 16,731, dated June 8, 1886.

UNITED STATES PATENT OFFICE.

CANDACE WHEELER, OF NEW YORK, N. Y.

DESIGN FOR THE DECORATION OF CURTAIN FABRICS, &c.

SPECIFICATION forming part of Design No. 16,731, dated June 8, 1886.

Application filed April 28, 1886. Serial No. 200,482. Term of patent 7 years.

To all whom it may concern:

Be it known that I, CANDACE WHEELER, a citizen of the United States, residing in the city, county, and State of New York, have 5 invented and produced a new and original Design for the Decoration of Curtains, Draperies, &c., of which the following is a specification, and which is illustrated in the accompanying photograph, which represents a portion of a surface so ornamented.

The design consists in a fabric having the representations, A, of pine-cones distributed irregularly over the surface to be ornamented, in connection with the conventionalized representations, B, of pine branches and the con-

fused or intermingled disconnected pine-needles C, the design being continued over the whole surface to be ornamented therewith.

I claim—

The design for curtains, draperies, and like fabrics, the same consisting of a curtain, drapery, or like fabric having upon its surface the conventionalized representations of pine branches, pine-cones, and disconnected and confused pine-needles, arranged substantially 25 as described and shown.

CANDACE WHEELER.
